UNITED STATES PATENT OFFICE.

JACOB J. FREEMAN, OF TOLEDO, OHIO.

DESIGN FOR A SPOON.

SPECIFICATION forming part of Design No. 22,376, dated May 2, 1893.

Application filed January 21, 1893. Serial No. 459,302. Term of patent 3½ years.

To all whom it may concern...

Be it known that I, JACOB J. FREEMAN, of Toledo, in the county of Lucas and State of Ohio, have originated and produced a Design for Spoons, &c., of which the following is a specification.

I will describe a spoon embodying the design it being understood that the design of the handle portion is equally applicable to forks, &c.

In the accompanying drawings, Figure 1 is a back view of a spoon and Fig. 2 is a front view thereof.

Similar letters of reference designate corresponding parts in both figures.

In the spoon which I have illustrated the bowl, A, bears, upon its inside surface a representation, in perspective, of the front and one corner of a building. The front surface or obverse O of the handle is embellished with a representation of a corn stalk, B, showing the leaves, b, and, here and there, an ear of corn, b'. About the leaves are two bands, C C', arranged diagonally across the front

surface of the handle. On the under surface 25 or reverse R of the handle is delineated a sword, D, the hilt thereof being toward the end of said handle, and the blade pointing toward the bowl. Supported by the ends of the leaves, I have shown a horse-chestnut E 30 upon which is sitting a frog F.

What I claim, and desire to secure by Letters Patent, is—

1. In the design for a spoon &c., the obverse O, substantially as shown and described. 35
2. In the design for a spoon &c., the reverse R, substantially as shown and described.
3. The design for a spoon &c. consisting of obverse and reverse, substantially as shown and described. 40

In testimony whereof I have signed my name to this specification in the presence of two subscribing witnesses.

JACOB J. FREEMAN.
